SCRAPER FOR BATTERY POSTS

Robert J. Plumley, Williamsville, N. Y.

Application November 27, 1944, Serial No. 565,367

2 Claims. (Cl. 15—236)

1

My invention relates to a device for cleaning battery connection members of the nature employed on batteries for automobiles.

The connection members of automobile batteries invariably consist of tapering battery posts extending upwardly from the top of the battery and contractible clip connectors adapted to be placed over the battery posts and fastened thereto, the opening through such connectors tapering in one direction to conform to the taper of the battery posts.

Verdigris and dust, dirt and other foreign matter accumulate on these connections, causing corrosion and otherwise rendering the electrical connection thus established between the battery and its current-conducting wires less effective. A bad electrical connection is, therefore, established and maintained unless the parts or members forming the connection between the battery and current-conducting wires are maintained in clean condition. This, however, has been quite difficult due to the fact that so far as known by applicant, no means has been provided for cleaning battery posts or the connectors to which the current-conducting wires are secured; it being common practice to resort to the use of a cloth or rag, or a brush, both unsuitable for the purpose, with the result that the connector members or elements are only partly cleaned and in a short time verdigris with dust and dirt accumulating again quickly builds up and the efficiency of the battery is considerably reduced.

One of the objects of my invention is to provide a tool of the kind mentioned which is simple in construction, inexpensive, and easily operated so as to enable the owner or user of a car to maintain the connections to the battery in clean condition, equaling or at least closely approaching that existing when a new battery and new connectors thereto are employed.

Another object of my invention is to provide a tool of the kind mentioned by means of which the peripheral surface of a binding post can be scraped by applying the required tension to the tool without wearing away any portion of the binding post and whereby the interior or contacting surface of a clip connector designed to be placed over the binding post may be scraped to free it of verdigris or other undesirable matter without cutting into and removing any portion of the clip connector.

A further object of my invention is to provide a tool of the kind mentioned with spaced-apart members having means to scrape the peripheral surface of a binding post and means for strad-

2

dling the binding post while scraping the same so as to prevent accidental displacement of the tool during the act of scraping the post, and which also is provided with means for scraping the interior of a clip connector adapted to be clamped onto a binding post and with rider means whereby the scraping means may be more effectively guided around the wall of the hole or opening in the connector and the tension applied to the scraping means regulated more effectively.

10 In the drawings:

Fig. 1 is a front elevation of my improved cleaning device or tool, showing the same applied to a binding post of a battery, such as used in automobiles.

15 Fig. 2 is a side elevation viewed from the left of Fig. 1.

Fig. 3 is a side elevation viewed from the right of Fig. 1.

20 Fig. 4 is a cross section taken on line 4—4, Fig. 3.

Fig. 5 is a cross section taken on line 5—5, Fig. 1.

25 Fig. 6 is a front elevation of the tool, showing the same inserted into a clip connector, a portion of the handle of the tool being broken away.

Fig. 7 is a longitudinal section taken on line 7—7, Fig. 6, looking in the direction of the arrow crossing said line.

30 Fig. 8 is a cross section taken on line 8—8, Fig. 6.

In this improved device I provide two arms or members which are or may be flexibly connected together at one of their ends and which have their opposite ends free and capable of movement relatively toward and from each other due to their flexible connection.

35 In preferred form, I construct this tool of a flat strip of metal bent centrally between its ends to provide two elongated arms or members 10 and 11, which are spaced apart and connected by the curved bight 12 formed by bending the strip upon itself.

This strip is preferably formed of steel and 40 it is cyanide or otherwise hardened so that a degree of resiliency is imparted to the two arms or members 10 and 11. The arm or member 10 is curved transversely, as at 13, so as to provide a concavo-convex terminal for the same, 45 the radius of the inner surface of which is preferably smaller than the radius of the battery post, which latter is designated by the numeral 14 and extends upwardly from the battery proper, designated by the numeral 15. In 50 this manner sharp scraping edges or angles 16

are provided at the points where the edge faces of the arm 13 meet the concaved inner surface of the arm.

It is also to be noted that the two arms 10 and 11 are slightly flared or made diverging from the bight 12 to their free ends and the inclination thus given these arms approximates that of the upward taper of the battery post, such taper being usually provided for all posts of batteries.

The arm 11 is provided at opposite edges and near its lower end with notches 17, gradually deepened toward the free end of the arm, thus providing a narrowed and tapered portion 18 at such region of the arm. This narrowed taper portion is disposed opposite the major portion of the concavo-convex terminal 13 of the arm 10. At the extremity of the arm 11 laterally projecting curved lugs 19 extend from opposite edges thereof, the region of this arm embracing said lugs being made concavo-convex and being adapted to ride over the peripheral face of the battery post.

This tool is designed to have its lower end fitted over the battery post with the arms 10 and 11 thereof engaging opposite sides of the post and it is to be rotated around the post or oscillated thereon so that verdigris and all other matter adhering thereto may be scraped therefrom by the edges or angles 16 formed by the flat edges of the arm and their inner concaved surfaces at the concavo-convex region 13, in the manner clearly illustrated in Fig. 5.

For the purpose of conveniently rotating the tool, I prefer to pass through both arms near their upper ends a rod 20 serving as a handle, said rod serving to maintain the arms in their normally flared or diverging relation. By grasping this handle, the tool may be easily rotated continuously in one or the other direction while the lower end thereof is in engagement with the battery post, or it may be rotated back and forth traversing sufficient of the surface of the post so that the entire peripheral area will be cleared of adhering matter.

The rod or handle 20 may be loosely thrust through aligned openings in the two arms 10 and 11 so that the said arms may move inwardly on the rod or handle by exerting pressure with the hand against the outer sides of the device, the openings being so formed that the walls thereof normally 50 impinge against the rod and maintain the arms in proper flared or diverging relation. Under such action, the operating terminal of the arm 10 having the concavo-convex portion 13 will be forced against the battery post with the necessary 55 pressure. Such pressure, however, may be provided by the inherent resiliency of the arms, which, however, I do not consider as practicable for use by inexperienced persons.

When the rod or handle is passed loosely 60 through the two arms or members 10 and 11 of the tool, the bight 12 at the upper end of the tool serves as the fulcrum point for the arms.

If desired, the rod or handle may be passed through the two arms or members of the tool 65 with a tight fit so that movement on the rod or handle is prevented. In that case, a fulcrum point is established for each arm at the region through which the rod or handle is passed. Under such conditions slightly more pressure 70 against the outer faces of the arms or members may be required to create the contact-pressure which the scraping edges or angles 16 are to exert against the battery post; but when the resiliency of the connection for the arms is relied upon, the 75

necessary pressure is automatically applied, due to the divergence of the arms and the taper of the battery post.

The flaring of the two arms 10 and 11 of the tool permits the tool to be easily positioned over a battery post with the terminals of the arms against opposite sides of the latter. The flat inner face at the lower end of the notched portion of the arm 11 will bear against one side of the battery post, while the scraping edges or angles 16 at the lower concavo-convex portion of the arm 10 bears against the opposite side of the post, it being preferable to have the radius of the concaved inner surface of the arms smaller than the radius of the peripheral surface of the battery post. At the same time the lugs 19 at the end of the arm 11 straddle the battery post and prevent the tool accidentally riding off the post while rotating the tool to scrape the latter.

It will be apparent that when using this tool on a battery post, the concavo-convex terminal of the arm 10 serves as the operating or scraping element of the tool while the lower end or terminal of the arm 11 serves as a rider element which moves in contact with the battery post and also prevents the tool slipping from the post when under action to free the post from adhering matter.

Since battery posts invariably have a slight taper upwardly from the body of the battery, the usual clip connector applied thereto for connecting the current-conducting wires therewith, has a post-receiving hole or opening 21 therethrough to receive the battery posts. In Figs. 6 and 7 I have illustrated a connector of this type and in these figures, 22 designates the connector considered as a whole. The conventional type of connector illustrated comprises a short sleeve 23 open or split, as at 24, and at opposite sides of the open or split region it is provided with outstanding lugs 25. Through these lugs a clamping and securing bolt 26 is passed, onto which a nut 27 is threaded and when the latter is tightened on the bolt, the opening 21 formed in the sleeve is reduced in diameter. The opening normally is of a size so that the connector may be easily passed over the battery post 14 and when tightening the nut 27 on the bolt 26, this connector is securely fastened to the battery post. Diametrically opposite the lugs 25, a boss 28 extends from the sleeve 23 and into this boss the current-conducting wire 29 is secured.

Since verdigris and other matter forms on or adheres to the battery post, the wall of the hole or opening 21 in the sleeve 23 may become coated with verdigris and other foreign matter and this improved tool is also designed to free the wall of the opening of such matter. It may here be stated that the hole or opening in the sleeve 23 tapers upwardly to conform to the taper of the battery post.

When using this tool to scrape the wall of the opening in the sleeve of this connector, the tool is thrust into the opening 21, preferably from the bottom, as shown in Figs. 6 and 7. Normally the ends of the arms or members 10 and 11 are separated under their inherent resiliency to a degree that will necessitate opposite pressures being applied to the outer sides of these arms to diminish the distance between them and so that their lower ends lie within a region smaller than the smaller end of the opening in the connector. This will enable the free ends of the arms to be passed through said opening, preferably from

the larger end of the latter, and upon relieving the pressure applied to said arms, they will immediately expand or spring outwardly and engage the tapering wall of said opening. These arms are, of course, so positioned that the narrowed taper portion 18 of the arm 11 will lie in contact with the full length of the wall of the opening; due to said wall being tapered. At such times the retainer lugs 19 and the extremity of the concavo-convex portion of the arm 10 will extend through the upper end of the sleeve 23 of the connector, as clearly shown in Fig. 6, while the adjacent convexed exterior surface of the arm 10 will engage the wall of said opening and the scraping edges of the narrowed taper portion 18 of the arm 11, to be now described, will engage said wall at spaced apart points. The edges of the arm 11 are beveled outwardly as shown in Figs. 5 and 7 so as to provide tapering sharp scraping edges or angles 30. By reason of tapering the scraping edges or angles 30, they lie in contact throughout their lengths with the tapering wall of the opening in the connector and compensate fully for the contrary disposition of that portion of the arm 11 extending through said opening. Upon rotating the tool in the manner already stated, these scraping edges ride in contact with the inner face of the opening in the connector and scrape the same to free it from any adhering matter.

It will be apparent, therefore, that when using the tool as a scraper for a battery post, the concavo-convex portion 13 of the arm 10 serves as the scraping element while the flat narrowed taper portion 18 of the arm 11 and that region of the latter having the lugs 18 thereon serve as a rider or guiding medium, and that when utilizing the tool to scrape the wall of the opening in the connector, the said narrowed taper portion of the arm 11 serves as a scraping medium while the concavo-convex portion of the arm 10 serves as a rider or guiding medium.

For convenience in description, I refer to the connected ends of the arms 10 and 11 as the upper end of the tool or device while the free ends of said arms are referred to as the lower end thereof. It will, however, be apparent that the tool or device may be operated in any of various positions, but in most instances, and especially when scraping battery posts, the tool will be positioned with its handle at the top even though the tool is shown inverted in Fig. 6 of the drawing. By reversing the connector from the position shown in Fig. 6, the tool will be used in the position shown in Figs. 1, 2, 3.

Under the terms of the claims appended hereto, my improved tool need not necessarily be constructed of flat strip material, since it is possible to provide flexible arms or members functioning in the manner described from material otherwise shaped, or from a tube which may be slotted lengthwise at diametrically-opposite sides to provide spaced apart arms adapted to straddle a

battery post or to be inserted through an opening in a connector of a current-conducting wire. Other changes may be resorted to without departing from my invention as defined in the claims hereof or sacrificing any of the advantages thereof.

Having thus described my invention what I claim is:

1. A tool for cleaning battery posts, comprising spaced-apart flexible arms connected together at their upper ends and having free lower ends, one of said arms having a flat lower portion facing inwardly and adapted to ride in contact with a battery post at one side thereof and the other arm being adapted to be disposed against the battery post at the opposite side thereof and being transversely curved to provide longitudinal scraping edges to contact the peripheral surface of the battery post in spaced-apart relation to the flat lower portion of said first-mentioned arm, said first-mentioned arm having inwardly curved lugs extending from its extremity at opposite edges thereof adjacent said flat lower portion.

2. A tool for cleaning battery posts and connectors therefor, comprising two spaced-apart flexibly-connected arms formed of a flat strip of metal curved upon itself mid-way between its ends so as to provide connected upper ends for said arms and free lower ends, the lower end of one of said arms being reduced in width and tapered downwardly and its extremity provided with inwardly-curved lugs adapted to straddle a battery post, the edges of said reduced portion being beveled outwardly, the lower end of the other arm being curved transversely opposite the reduced and tapered portion of said first-mentioned arm to provide a terminal having a concaved inner surface, the edges formed by the angles of the edge faces of said arm and said concaved inner surface serving as scraping edges, and a rod thrust through said arms near their upper ends serving as a handle for the tool and as a means for maintaining said arms in normal diverging relation.

ROBERT J. PLUMLEY.
